UNITED STATES PATENT OFFICE.

GEORGE FRANK E. PEARSALL, OF BROOKLYN, NEW YORK.

DESIGN FOR A PHOTOGRAPH-MOUNT.

SPECIFICATION forming part of Design No. 20,840, dated June 16, 1891.

Application filed April 23, 1891. Serial No. 390,181. Term of patent 7 years.

To all whom it may concern:

Be it known that I, GEORGE FRANK E. PEARSALL, of Brooklyn, in the county of Kings and State of New York, have invented 5 a new and original Design for Mounted Photographic Prints; and I do hereby declare that the following specification, taken in connection with the drawing annexed to and forming part of the same, furnishes a full and clear description thereof.

The drawing is a front elevation of my design.

The design consists in a rectangularly-shaped background A, having ragged edges 15 a, and a rectangularly-shaped print or photo-

graph B, placed within the field of said background, and also provided with ragged edges b, as shown.

At the upper left-hand corner of the print a seal C, of wax or other material, is placed, 20 having a figure or character upon it in relief.

What I claim is—

The design for mounted photographic prints, as herein set forth and represented in the drawing.

G. FRANK E. PEARSALL.
